SELF-CONFORMING, SURFACE-GRIPPING,
READY-MADE KNITTED SLIP COVER FOR
OVERSTUFFED UPHOLSTERED FURNI-
TURE

Joseph A. Krasnov, Philadelphia, and Max M. Kuller, Allentown, Pa., assignors to Sure-Fit Products Company, Darby, Pa., a co-partnership composed of Joseph A. Krasnov and Samuel Krasnov

Application July 3, 1941, Serial No. 406,998

12 Claims. (Cl. 66—170)

The present invention relates to a new and useful slip cover for overstuffed upholstered furniture, and relates more particularly to a ready-made knitted slip-cover, which will have not only the stretchability of an ordinary knitted slip-cover such as that of United States Patent No. 2,100,868, but which will grip the surface and better conform to the shape of the overstuffed upholstered furniture, by virtue of a certain peculiar construction of the fabric panels of which the slip-cover is composed, whereby the tendency of the slip-cover to shift on the furniture is much reduced, so that a more perfect fit and appearance is obtained, coupled with a greater adjustability of the slip-cover (to varying sizes and shapes of overstuffed furniture) than has been obtainable heretofore by such construction as that of United States Patent No. 2,100,868.

With the above and other objects in view which will appear more fully from the following description and accompanying drawings, the present invention consists of a ready-made knitted slip-cover for overstuffed upholstered furniture, composed of knitted fabric panels and sections formed of a soft knitted cotton base which is stretchable and whose threads and loops do not have a hard but instead a soft and more or less fuzzy thread surface, and covered-rubber threads inter-knitted with the cotton threads and extending through the fabric in such a way as to pull and contract the fabric in two directions generally transversely of each other, thereby drawing the fabric together into a series of pocket-like formations which, when partly stretched over an overstuffed upholstered furniture, will cause the slip-cover panels to get a firmer grip upon, or better to hug the surface of the furniture and thus prevent slipping or sliding of the slip-cover over the furniture.

The present invention further consists of other novel features and details of construction, all of which will appear more fully from the following description and accompanying drawings and the appended claims.

For the purpose of illustrating the invention, there is shown in the accompanying drawings a form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as hereinafter shown and described.

In the accompanying drawings, in which like reference characters indicate like parts,

Figure 1 represents a perspective view of a ready-made knitted slip-cover embodying the present invention shown as applied to an overstuffed armchair.

Figure 2 represents a bottom perspective view thereof.

Figure 3 represents a fragmentary portion of the under surface of the fabric panels composing the knitted slip-cover of the present invention, in one embodiment thereof;—shown approximately on a full-size scale.

Figure 4 represents a fragmentary portion of the outer surface of the fabric panels composing the knitted slip-cover of the present invention, in one embodiment thereof, namely, the embodiment of which Figure 3 shows the opposite surface;—shown approximately on a full-size scale.

Figure 5 represents a plan view of the fabric structure viewed from the outer surface, namely, the surface shown in Figure 4, but shown on a much enlarged scale, namely, a scale of approximately ten or fourteen times actual size, and shown more or less schematically, insofar as the thread formations are shown as they would appear if the fabric were stretched out completely, in both directions, so as to better show the interlacings of the cotton and covered-rubber threads;—the courses extending parallel to the greater dimension of this figure, and the wales extending parallel to the smaller dimension of this figure (this figure representing the embodiment shown in Figures 3 and 4).

Figure 6 represents a plan view of the fabric structure viewed from the inner surface, namely, the surface shown in Figure 3, but shown on a much enlarged scale, namely, a scale of approximately ten to fourteen times actual size, and shown more or less schematically, insofar as the thread formations are shown as they would appear if the fabric were stretched out completely, in both directions, so as to better show the interlacings of the cotton and covered-rubber threads;—the courses extending parallel to the greater dimension of this figure and the wales extending parallel to the smaller dimension of this figure (this figure representing the embodiment shown in Figures 3 and 4).

Figure 7 represents a perspective view of the slip-cover, similar to that shown in Figure 1, but with the seam lines shown.

Figure 8 represents a perspective view of a detachable skirt which is shown in and applied in Figure 7.

Figure 9 represents a perspective view of the slip-cover taken apart into four parts to show the manner of its formation and assembly; while Figure 10 represents a perspective view of the cushion part of the slip-cover of the present invention.

Figures 11 and 12 represent cross-sectional views, taken on lines 11-11 and 12-12, respectively, of Figure 7.

Many attempts have been made to obtain a self-conforming ready-made slip-cover for overstuffed upholstered furniture, which will fit an upholstered armchair, for instance, with some latitude as to shape, contour and dimensions of the chair. U. S. Patents 2,100,868, 2,212,485 and 2,098,684 represent some of these efforts. These and other past efforts have still left something to be desired in the final appearance and effectiveness of ready-made slip-covers, particularly in respect to their ability to "stay put" on the upholstered furniture, while the furniture is being actively used.

We have found that by forming the surface of the fabric panels of a ready-made knitted slip-cover (particularly those fabric panels most subject to be shifted and pulled and dislodged when the upholstered furniture encased in such slip-cover is in active use) with a multiplicity of self-contracting pocket-like formations, which therefore present, at once, a reduced contact area between the slip-cover panels and the original surface of the upholstered furniture and at the same time tend to grip or hug the original surface of the upholstered furniture, the slip-cover better "remains put" on the upholstered furniture against the normal tendency to shift and pull and dislodge the slip-cover by sitting upon it, or leaning on the arms, or getting up from the chair or otherwise applying dislodging forces to the slip-cover.

We have found that by a combination of a relatively soft knitted cotton base, and covered-rubber threads interknitted therewith at suitable intervals and so interknitted with the soft knitted cotton threads as to contract the fabric in two directions, a surface-gripping effect is attained which is highly effective to keep the slip-cover in place and which also materially increases the range of size and shape variations, in the upholstered furniture piece, which the same slip-cover can satisfactorily and adequately "fit" without any special or individual adjustment (as by taking in or letting out a seam or two) of the ready-made slip-cover.

Moreover, by the present invention, the panels of the ready-made slip-cover which fit over concave surfaces of the upholstered furniture, as, for instance, the outer surfaces of the arms which are undercut or concaved, tend to enter the concavity and tend better to conform to the concave configuration of the furniture.

In carrying out the present invention we may form the fabric panels of knitted fabric like that shown in Figures 3, 4, 5 and 6, which may be made either on a flat knitting machine or a circular knitting machine;—preferably the latter. Thus, for instance we may form the fabric on a multi-feed circular latch-needle type knitting machine, of suitably large diameter, as, for instance, a circular knitting machine containing 1,080 needles in the cylinder thereof and having a multiplicity of feeds, as, for instance 28 or 32 feeds for feeding yarn to the needles. A machine suitable for this purpose is the "Supreme" circular knitting machine made by the Supreme

Knitting Machine Company of Brooklyn, New York;—although any other equivalent or suitable knitting machine may be used.

Every sixth or seventh yarn feed is fed or supplied with a covered-rubber thread, while the rest of the yarn-feeds are fed or supplied with soft-twisted cotton or mercerized cotton threads. In this manner every sixth or seventh or so course is knitted of the covered-rubber yarn. Thus, for instance, on a 32-feed circular knitting machine, 28 of the feeds may be used, with every seventh feed supplied with a covered-rubber yarn or strand and the intervening six feeds (that is, those between two successive rubber feeds) supplied with a soft low-twist cotton yarn or mercerized cotton yarn. Similarly, if every sixth feed is to be rubber, 30 of the feeds may be used; five feeds rubber and twenty-five feeds cotton;—with five cotton feeds intervening successive rubber feeds.

In the schematic views of Figures 5 and 6, we have illustrated a seven-to-one cotton and rubber course arrangement, in which every seventh course is knitted of covered-rubber yarn 11, while the intervening courses are knitted of cotton yarns 12.

As will be seen from Figures 5 and 6, every sixth needle is caused to remain in an inoperative position at the cotton feeds, but to remain operative at the rubber feeds. In this manner, the six cotton threads 12 forming the six successive courses intervening to successive rubber courses, are caused to float across and within the rubber loops 13, as for instance at 14. After each rubber course, the needles rendered inactive or inoperative at the cotton feeding points, are staggered in relation to each other as shown clearly in Figures 5 and 6. This causes certain areas to be bounded on all sides by rubber, as shown in Figures 5 and 6, so as to cause the rubber in the fabric to contract the fabric in two directions, that is in a direction parallel to the courses and in a direction at right angle to the courses. This 2-way contraction of the fabric causes pocket-like formations to be formed, each pocket being bounded by rubber, as indicated particularly in Figures 3 and 4;—with the ridges 15, separating the pockets 16, serving as reduced contact areas between the fabric panels of the slip-cover and the original fabric surface of the upholstered furniture. In the alternative, the surface shown in Figure 4 may be used as the contact surface, as this also presents reduced contact areas;—the contact areas here being however the convex protuberances 17 shown in Figure 4.

The main slip-cover is formed preferably of four sections or four pieces of fabric, one forming the back-encasing portion 18, the other forming the seat and front portion 19 and the other two forming the left and right arm-encasing side portions 20 and 21 respectively. Each of the sections 18, 20, 21 is formed by folding the fabric back upon itself to form a pocket-like upper portion with the outer portion extending further down to encase the corresponding vertical side of the upholstered furniture. Thus, the back-encasing portion 18 is formed by folding a piece of fabric into rear and front panels 22 and 23, respectively;—with the rear panel 22 extending to the lower edge line 24 of the furniture and extending beneath the furniture in the form of a securing tab 25. The side members 20 and 21, are likewise formed by folding a piece of the fabric into a pocket-like formation, closed at the

top and open at the bottom, and each member composed of an inner panel 26 and 27 respectively, and an outer panel 28 and 29, respectively, which latter likewise extend down to the lower furniture line 24, where they are folded under to form securing tabs 30 and 31, respectively.

The front and rear panels 22 and 23 of the back-encasing portion 18 are seamed along the vertical side-seams 32 and 33, while the side members 26 and 27 are seamed along the front vertical seams 34 and 35, respectively, and possibly also along short upper horizontal seams 36 and 37, respectively, particularly where the front ends of the arms come to a more or less abrupt edge (as distinguished from the rounded upper corners of the back as shown in the drawings). The front and seat portion 19 includes the seat panel 38 and the front panel 39 which also extends down to the bottom edge 24 of the furniture, where it is folded inwardly to form a securing tab 40. The four sections 16, 19, 20 and 21 are then united along the seaming edges 41-a and 41-b, 42-a and 42-b, 43-a and 43-b, 44-a and 44-b, 45-a and 45-b, 46-a and 46-b, 47-a and 47-b, 48-a and 48-b, 49-a and 49-b, 50-a and 50-b and 51-a and 51-b, to form the inter-sectional seams 44, 42, 43, 44, 45, 46, 47, 48, 49, 50 and 51 (shown in Figure 7).

Because of the relatively soft character of the basic fabric and the 2-way contraction thereof, and the formation of the series of concavities on one side and convex protuberances on the other side, the seam lines are substantially obliterated or rendered considerably obscure in the finished product;—the seams being formed by an overlock stitch which gathers the two adjacent edges, which gathered edges are formed on the inside of the slip-cover, where they are not visible.

Tubular hems 52, 53, 54 and 55 are provided along the inner edges of the securing tabs 28, 30, 31 and 40, which may be formed of the same fabric as of which the slip-cover is formed, or that may be formed of a separate piece of woven fabric such as a piece of strong woven cotton fabric, sewn to the edge of the securing tabs. Through these tubular hems a draw-string or cord 56 is drawn, in series, which can then be drawn together or tied at one point, as for instance at 57, in order to pull the securing tabs firmly together as indicated in Figure 2;—the securing tabs being sufficiently narrowed just to clear the legs 58, 59, 60 and 61 of the furniture.

A detachable skirt 62 may also be provided, in the form of a continuous piece of fabric, shirred along its upper marginal zone, and also preferably sewn to or bound by an upper marginal elastic band or cord 63 which will cause it to hug the basal portion of the furniture, just above the lower edge 24 of the furniture to give a finished effect.

The cushion 64 is formed completely to encase the separable cushion of the upholstered furniture with a suitable opening 65 in the rear through which the furniture cushion may be inserted;—the cushion casing being seamed along seams 66, 67 and 68, and being provided in the rear with a tubular hem 69 through which a raw-string and tie-string may be extended, or

the edge of the rear opening 65 may be bound with an elastic band or tape or cord which contracts the opening by reason of its elasticity.

While in the accompanying drawings, as for instance Figures 5 and 6, one form of construc-

tion is shown, it is to be understood that this may be varied both dimensionally and otherwise. Thus, for instance instead of rendering inactive every sixth needle at the cotton feed portions (or when the cotton feed reaches it), every fifth or seventh (or so) needle may be rendered inactive at this cycle of operation. The essential feature of our construction is that the elastic course, interspersed at suitable intervals, is caused to stretch across the several intervening courses non-elastic yarn, to contract the fabric also transversely of the courses, or wale-wise;—with the wale-wise contracting rubber loops (extending between successive rubber courses) being staggered.

By the present invention, the resultant ready-made slip-cover not only conforms more readily and with greater fidelity to the varying contour of the upholstered furniture, but the panels of the slip-cover tend to grip or hug the surface, of the upholstered furniture and resist dislodgment or "shifting" of the slip-cover upon the furniture, while in actual use.

In Figure 5, we have also illustrated, a fragmentary portion of the covered-rubber yarn 11, on a still further enlarged scale, showing the central rubber core portion thereof, and the two oppositely wound outer cotton, mercerized or rayon wrapping threads 71 and 72, which encase and cover the inner rubber core 70.

The inner back-panel 23 and the inner arm-panels 26 and 27 are made "full" in the zone of their lower edges 45-a, 46-b and 47-b, respectively, that is, they are extended a suitable distance 73 below the level or line 74 of the seat 15 of the chair or davenport or sofa. The seat panel 38 is made similarly "full" in the zones of its rear edge 45-b and of its side edges 48-a and 49-a, that is, these edge zones are also extended a suitable distance 73 beyond the corresponding horizontal dimensions of the seat 15 of the chair, davenport or sofa. The inter-sectional seams 45, 46 and 47 are accordingly extensible downwardly between the seat 75 and the back 45, 15 and arms 77 and 78, respectively, as shown more particularly in Figures 11 and 12. By tucking the excess material 73 in the marginal zones adjacent the seams 45, 46 and 47, between the rear and side surfaces 79, 80 and 81, respectively, of the seat 75 and the closely adjacent inner surfaces 82, 83 and 84 of the back and arms 16, 17 and 18, respectively, the slip-cover can be drawn and maintained taut over the back and over the arms of the chair, davenport or sofa, and over the front thereof, and all slack in the exposed portions of the fabric panels can thus be taken up.

By reason of the surface formations and contractions of the fabric panels of the slip-cover, the tucked-in portions 73 tend better to remain in place, in actual use.

Along the lower marginal edges of the slip-cover, intermediate the tubular hems 52, 53, 54 and 55, rubber or rubber-containing or other elastic tapes, band, or cords 85 are affixed, as by overlock stitches, or the like, thereby causing a tight, elastic encirclement of each of the legs 58, 59, 60 and 61, and any slight slack in the fabric, is further taken up.

The covered elastic strands or arms may be formed with a cord of other elastic materials, that is other than natural rubber, as for instance, synthetic rubber-like or elastic organic compositions used as substitutes for rubber or the equivalents of rubber. Therefore, in using the term "rubber," in the claims, it is to be understood that

this term is intended to comprehend equivalent materials such as a synthetic rubber-like elastic compounds and compositions used as substitutes for an equivalent of rubber.

In addition to the protuberances on one side and concavities and pocket-like formations on the other side of the panels of the slip-cover, the elastic thread within the panels of the slip-cover also tends to loosen some of the knitted loops of the relatively non-elastic cotton or similar thread, so that these loops will be limp and loose while the panel itself may, as a whole, be taut on the surface covered thereby. This effect of a tautly stretched panel some of whose knitted body loops of cotton or the like are relatively loose or limp, further tends to create a surface-gripping or surface-adherence effect in relation to the furniture surface covered thereby; these loose or limp cotton loops serving, in effect, as minor anchorages on the furniture surface covered by the panel.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described our invention, we hereby claim and desire to secure by Letters Patent, the following:

1. A ready-made self-conforming knitted slip-cover for furniture, comprising an encasing cover closed at the top and generally open at the bottom, formed of a knitted fabric composed of a preponderance of soft cotton yarn loops having interspersed therethrough rubber threads inter-knitted therewith and stretched both wale-wise and course-wise to contract the fabric in two directions to form reduced surface contact areas for contact with the surface of the furniture covered.

2. A ready-made self-conforming knitted slip-cover for furniture, comprising an encasing cover closed at the top and generally open at the bottom, formed of a knitted fabric composed of a preponderance of soft cotton yarn loops having interspersed therethrough rubber threads inter-knitted therewith and stretched both wale-wise and course-wise to contract the fabric in two directions so as to form series of concavities on one side of the slip-cover surface and corresponding protuberances on the other side of the slip-cover surface, thereby to resist shifting of the slip-cover upon the furniture.

3. A ready-made self-conforming knitted slip-cover for furniture, comprising an encasing cover generally closed at the top and generally open at the bottom; formed at least in part of knitted fabric panels composed of a preponderance of soft cotton yarn loops having interspersed therethrough covered-rubber threads inter-knitted therewith and stretched both wale-wise and course-wise to contract the fabric in two directions to form reduced surface contact areas for contact with the surface of the furniture covered.

4. A ready-made self-conforming knitted slip-cover for furniture, comprising an encasing cover generally closed at the top and generally open at the bottom, formed at least in part of knitted fabric panels composed of a preponderance of soft cotton yarn loops having interspersed therethrough covered-rubber threads inter-knitted therewith and stretched both wale-wise and

course-wise to contract the fabric in two directions so as to form series of concavities on one side of the slip-cover surface and corresponding protuberances on the other side of the slip-cover surface, thereby to resist shifting of the slip-cover upon the furniture.

5. A ready-made self-conforming knitted slip-cover for furniture, comprising an encasing cover closed at the top and generally open at the bottom, formed of a knitted fabric composed of a preponderance of soft cotton yarn loops having interspersed therethrough rubber threads inter-knitted therewith and stretched both wale-wise and course-wise to contract the fabric in two directions to form reduced surface contact areas for contact with the surface of the furniture covered, and leg-encircling elastic edgings affixed to the lower marginal zones of the slip-cover adjacent the legs of the furniture.

6. A ready-made self-conforming knitted slip-cover for furniture, comprising an encasing cover closed at the top and generally open at the bottom, formed of a knitted fabric composed of a preponderance of soft cotton yarn loops having interspersed therethrough rubber threads inter-knitted therewith and stretched both wale-wise and course-wise to contract the fabric in two directions so as to form series of concavities on one side of the slip-cover surface and corresponding protuberances on the other side of the slip-cover surface, thereby to resist shifting of the slip-cover upon the furniture, and leg-encircling elastic edgings affixed to the lower marginal zones of the slip-cover adjacent the legs of the furniture.

7. A ready-made self-conforming knitted slip-cover for furniture, comprising an encasing cover generally closed at the top and generally open at the bottom, formed at least in part of knitted fabric panels composed of a preponderance of relatively soft and relatively non-elastic loops having interspersed therethrough elastic threads inter-knitted therewith and stretched both wale-wise and course-wise to contract the fabric in two directions.

8. A ready-made self-conforming knitted slip-cover for furniture, comprising an encasing cover generally closed at the top and generally open at the bottom, formed at least in part of knitted fabric panels composed of a preponderance of relatively soft and relatively non-elastic loops having interspersed therethrough elastic threads inter-knitted therewith and stretched both wale-wise and course-wise to contract the fabric in two directions to form reduced surface contact areas for contact with the surface of the furniture covered.

9. A ready-made self-conforming knitted slip-cover for furniture, comprising an encasing cover generally closed at the top and generally open at the bottom, formed at least in part of knitted fabric panels composed of a preponderance of relatively soft and relatively non-elastic loops having interspersed therethrough elastic threads inter-knitted therewith and stretched both wale-wise and course-wise to contract the fabric in two directions so as to form a series of concavities on one side of the slip-cover surface and corresponding protuberances on the other side of the slip-cover surface, thereby to resist shifting of the slip-cover upon the furniture.

10. A ready-made self-conforming knitted slip-cover for furniture, comprising an encasing cover generally closed at the top and generally open at the bottom, formed at least in part of knitted

fabric panels composed of alternating preponderant groups of courses of knitted loops of a relatively non-elastic textile thread and minor courses of knitted loops formed of relatively elastic thread under tension, with the loops of the relatively non-elastic courses being dropped at spaced intervals and with the thread of the relatively non-elastic courses floated in an unknitted condition, at such spaced intervals, through an elastic loop, and with the floated portions of one group of relatively non-elastic courses being staggered in relation to the floated portions of adjacent groups of relatively non-elastic courses.

11. A self-conforming slip-cover for furniture such as chairs, sofas and the like, comprising an encasing envelope-like cover including a knitted fabric panel composed of a preponderance of relatively soft cotton yarn loops having interspersed therethrough and interknitted therewith covered-rubber threads tending to contract said panel both wale-wise and course-wise and to make some of the cotton loops relatively loose and limp when so contracted, whereby some of such knitted cotton loops will be loosely disposed

against the furniture surface covered while said knitted fabric panel is taut on the furniture surfaces covered thereby, so as to cause such panel better to grip the surfaces covered thereby and better to resist shifting on said furniture surface.

12. A self-conforming slip-cover for furniture such as chairs, sofas and the like, which comprises an encasing envelope-like cover including a knitted fabric panel composed of alternating preponderant groups of courses of knitted loops of relatively non-elastic textile thread and minor courses of knitted loops interknitted therewith formed of relatively elastic thread alternating with such preponderant groups of courses, with the thread of one of the two kinds of courses floated in an unknitted condition through the loops of the other of the two kinds of courses, and with the floated portions of the thread of some of said float-containing courses staggered in relation to the floated portions of the thread of other of said float-containing courses.

JOSEPH A. KRASNOV.
